SHREDDER

Joseph W. Chambers, Sr., Rancho La Costa, Calif., assignor to Atomic Disposer Corporation, a subsidiary of Elixir Industries

Filed Jan. 26, 1973, Ser. No. 326,812

Term of patent 14 years

Int. Cl. D15—09

U.S. Cl. D55—1 B

FIG.1

FIG.2

FIG.3

FIG.4

FIG.5

FIG. 1 is an elevational side view of a shredder showing my new design;

FIG. 2 is an elevational right hand side view of said shredder;

FIG. 3 is an elevational front view of said shredder;

FIG. 4 is a top view of said shredder; and

FIG. 5 is a rear view of said shredder.

I claim:

The ornamental design for a shredder, substantially as shown.
